UNITED STATES PATENT OFFICE

2,083,807

TWO-CYCLE ENGINE

Albert Andrews, Deadwood, S. Dak.

Application June 26, 1935, Serial No. 28,575

4 Claims. (Cl. 123—52)

The invention aims primarily to provide a new and improved two-cycle internal combustion engine of simple inexpensive and well balanced construction, capable of developing great horse power and therefore well adapted for driving land, water or air craft. Two oppositely rotatable crank shafts are provided, driven by two rows of power pistons, said crank shafts serving also as actuating means for pump pistons which force explosive gas into the power cylinders to expel the exhaust gases therefrom and to recharge them, and said crank shafts may well be employed to drive two propellers in opposite directions to counterbalance the torque thereof.

With the above and minor objects in view, the invention resides in the novel subject matter hereinafter described and claimed, description being accomplished by reference to the accompanying drawings, wherein:

Fig. 1 is a top plan view.
 Fig. 2 is a longitudinal sectional view partly in elevation as indicated by line 2—2 of Fig. 1.
 Fig. 3 is a vertical transverse sectional view on the irregular line 3—3 of Fig. 1.

A preferred construction has been illustrated and while this construction will be rather specifically described, variations may be made within the scope of the invention as claimed.

A crank case 5 having a suitable pan 6 carries two rows of power cylinders 7 and a row of gas-pumping cylinders 8, the cylinders 7 being preferably located similarly to those of a V-type motor and the cylinders 8 being disposed between the two rows of cylinders 7. The cylinders 7 are preferably formed in two separate blocks 9 having water jackets 10 but the cylinders 8 may be air-cooled, for which purpose fins 11 are shown.

The cylinders 7 contain power pistons 12 connected by rods 13 with the cranks 14 of two parallel crank shafts 15 which rotate in opposite directions. In a motor such as herein disclosed, having eight power cylinders, the cranks 14 are set 90° apart and the engine is preferably timed so that the first two cylinders fire first; the next two, second; the third two, third; and the fourth two, last. The pistons 12 act as the sole valve means for gas admission ports 16 and exhaust gas ports 17 which are formed through opposite portions of the side walls of the power cylinders 7.

The gas-pumping cylinders 8 contain gas-pumping pistons 18 which are connected by diverging rods 19 with the cranks 14 of the crank shafts 15. The rods 19 may either connect di-

rectly with the cranks 14 or may be pinned at 20 to the power rods 13. Thus, the same cranks which are used in transmitting rotary motion to the shafts 15 act as actuating means for the pump pistons 18 and by using the diverging rods 19, the pistons 18 have no lateral throw to create wear and eventually cause piston slap.

Each pumping cylinder 8 is provided with a gas admission check valve 21 communicating with an intake manifold 22 leading from a suitable carburetor, and the side wall of each of said cylinders 8 is provided with two gas discharge ports 23 for communication with the lower ends of gas discharge passages 24 formed in the pistons 13. Gas-conducting pipes 25 lead from the gas discharge ports 23 of the cylinders 8 to the gas admission ports 16 of the power cylinders 7, in such manner that the gas compressed in one cylinder 8 will drive out the exhaust gases from two of the power cylinders 7 and recharge the latter, the gas compressed in another of the cylinders 8 will similarly scavenge and recharge another pair of the power cylinders 7, etc.

Fig. 3 illustrates two of the power pistons 12 at the ends of their power strokes and illustrates also the piston 18 and cylinder 8 which serve the power cylinders 7 of said pistons 12. By the time these pistons 12 reach the ends of their power strokes, they have opened gas admission ports 16 and the gas exhaust ports 17, and piston 18 has ascended and brought the ports 24 in communication with the ports 23. The result is that the gas compressed above the piston 18 (admitted through valve 21 on the previous descent of said piston 18) is forced through the passages 24, ports 23, pipes 25 and ports 16 into the cylinders 7, thereby driving out the spent gases through the exhaust ports 17 and recharging said cylinders 7. When the pistons 12 ascend, this gas is compressed in readiness for firing, effected by conventional ignition means including spark plugs 26. As the power pistons 12 ascend, pump piston 18 descends, drawing in fresh gas into the cylinder 8 in readiness for compression.

It will be seen from the foregoing that simple and advantageous construction has been provided for carrying out the objects of the invention.

The engine may be used for driving any selected load but for illustrative purposes, I have shown two oppositely driven propellers 27 which may be operatively connected with the two crank shafts 15 in the manner disclosed in my pending application Serial No. 28,574 filed June 26, 1935.

I claim:

1. In a two-cycle internal combustion engine, two rows of power cylinders, power pistons in said power cylinders, two oppositely rotatable crank shafts, rods connecting the pistons of one of said rows of power cylinders with the cranks of one of said crank shafts, other rods connecting the pistons of the other row of power cylinders with the cranks of the other crank shaft, and 5 scavenging and charging means for said power cylinders including a row of gas-pumping cylinders, pumping pistons in said gas pumping cylinders, and diverging rods connected to said pumping pistons and actuated by the same cranks with 10 which the aforesaid rods are connected, there being two of said diverging rods connected with each one of said pumping pistons, one of these rods being operatively connected with a crank of one of said crank shafts and the other operatively connected with a corresponding crank of the other of said crank shafts.

2. In a two-cycle internal combustion engine, two rows of power cylinders, power pistons in said power cylinders, two oppositely rotatable crank 25 shafts, rods connecting the pistons of one of said rows of power cylinders with the cranks of one of said crank shafts, other rods connecting the pistons of the other row of power cylinders with the cranks of the other crank shaft, and scaveng- 30 ing and charging means for said power cylinders including a row of gas pumping cylinders between said rows of power cylinders, pumping pistons in said gas-pumping cylinders, and diverging rods connected to said pumping pistons 35 and actuated by the same cranks with which the aforesaid rods are connected, there being two of said diverging rods connected with each one of said pumping pistons, one of these rods being operatively connected with a crank of one of said 40 crank shafts and the other operatively connected with a corresponding crank of the other of said crank shafts.

3. In a two-cycle internal combustion engine, two rows of power cylinders, each having opposed 45 gas admission and gas exhaust ports, power pistons in said power cylinders acting as valves for said ports, two oppositely rotatable crank shafts, rods connecting the pistons of one of said rows of power cylinders with the cranks of one of said 50 crank shafts, other rods connecting the pistons

of said other row of power cylinders with the cranks of the other crank shaft, a row of gas pumping cylinders each having a gas admission valve and opposed gas discharge ports, gas pumping pistons in said gas pumping cylinders each having two gas discharge passages for communication with said opposed gas discharge ports of said gas pumping pistons, diverging rods connected to said gas pumping cylinders and actuated by the same cranks with which the aforesaid rods are connected, there being two of said diverging rods connected with each one of said pumping pistons, one of these rods being operatively connected with a crank of one of said crank shafts and the other operatively connected with a corresponding crank of the other of said crank shafts, and gas conducting passages leading from said gas discharge ports of said gas pumping cylinders to said gas admission ports of said power cylinders.

4. In a two-cycle internal combustion engine, two rows of power cylinders each having opposed gas admission and gas exhaust ports, power pistons in said power cylinders acting as valves for said ports, two oppositely rotatable crank shafts, rods connecting the pistons of one of said rows of power cylinders with the cranks of one of said crank shafts, other rods connecting the pistons of said other row of power cylinders with the cranks of the other crank shaft, a row of gas pumping cylinders between said rows of power cylinders and each having a gas admission valve and opposed gas discharge ports, gas pumping pistons in said gas pumping cylinders each having two gas discharge passages for communication with said opposed gas discharge ports of said gas pumping cylinders, diverging rods connected to said gas pumping pistons and actuated by the same cranks with which the aforesaid rods are connected, there being two of said diverging rods connected with each one of said pumping pistons, one of these rods being operatively connected with a crank of one of said crank shafts and the other operatively connected with a corresponding crank of the other of said crank shafts, and gas conducting passages leading from said gas discharge ports of said gas pumping cylinders to said gas admission ports of said power cylinders.

ALBERT ANDREWS.
